United States Patent Office.

A. E. DUPAS, OF NEW ORLEANS, LOUISIANA.

Letters Patent No. 99,300, dated February 1, 1870.

IMPROVEMENT IN ELECTRO-MAGNETIC MACHINES.

The Schedule referred to in these Letters Patent and making part of the same.

I, A. E. DUPAS, of the city of Paris, France, but now residing in the city of New Orleans, State of Louisiana, have invented certain improvements on my electro-magnetic machine, for which Letters Patent of the United States were granted me on the 17th day of August, 1869, which I call a "Duplex Armature Vibrating Electro-Magnetic Engine," of which the following is a specification.

Nature and Objects of the Invention.

The first part of my invention or improvement relates to a combination of a multipolar magnet, which can be extended indefinitely, so as to embrace any number of poles, according to the power required to be brought into development, in such a manner that both extremities of the same are always in magnetic equilibrium, with the object of preventing unnecessary wear of the central pivots, or articulating joints, on or at which the frame supporting the armatures vibrates.

The second part of my invention relates to the combination of a double-vibrating exactly-balanced frame, with rectangular partially-hollow armatures, connected with and supported at the two vibrating extremities of the same, with the object of acquiring the greatest possible magnetic momentum, and hence the production of any given power with the least possible amount and weight of metal.

The third part of my invention relates to a peculiar mode of making the magnetizing-coils employed in my engine, in order to pass the current of electricity around the electro-magnet, at right angles to the axis of the latter, and always in the same direction, whatever the number of coils required or used in the engine.

As in the case of my electro-magnetic machine, patented as aforesaid, on the 17th day of August, 1869, my present improvement is especially designed as a motor for operating sewing-machines, or the like, in which no great measure of power is requisite to the efficient working of the same.

Description of the Accompanying Drawings.

Figure 1 is a bottom view of a platform or table, on which a sewing-machine is fixed, with my engine attached thereto;

Figure 2, a side elevation;

Figure 3, an end view of the same table, &c., with the rear-side supporting-legs withdrawn or removed; and

Figure 4, a detached view of a section of a magnetizing-coil, as constructed by me, for use in connection with my engine.

General Description.

A A' are brackets, pendent from the lower side of a table, B, to which they are firmly fastened, by which

the multipolar electro-magnet C C' C", the partially-hollow armatures D D', and the vibrating frame E are secured, and supported in the position shown in the drawings.

The multipolar magnet C C' C" is supported by the axis F, of the vibrating frame E, which passes through its poles, and thus constitutes the base or "culasse" of the magnet, in the operation of the machine. The culasse of the magnet, in other words, constitutes the axis on which the frame E vibrates.

The armatures D D' are slightly concave, on the sides next the magnet, in order to conform to the slightly-curved extremities of its poles, so that they can hence be maintained in close proximity thereto during the vibration of the frame E. The forces being exactly balanced, will, of course, prevent any positive contact between the armatures and the poles of the magnet, and hence there can be neither friction nor wear of the parts.

On the three other sides, the armatures D D' have perfectly straight lines and plane surfaces, and hence, I call them rectangular, although, in very strictness of language, they are not so. They are made partially hollow by the recesses or hollow spaces H. H', and are, therefore, of exceeding lightness, as compared to what they would be if solid, while yet possessing the same power they would then have.

It may be, that under some circumstances, I might wish to combine the hollow cylindrical armature, employed in my patented machine, with my herein-described engine, and I wish to reserve the right to do so, if I shall consider it advisable.

The operation of closing and breaking the circuit in my present improvement, is accomplished by a modification of the same means described in the specification annexed to my patent of August 17, 1869, and in substantially the same way, so as to allow the armatures and their supporting-frame to complete such stroke by their momentum. Nor is there any sufficient difference between my manner of connecting this improvement with a sewing-machine, or the like, and that described in my said patent, to require a special description herein. It is enough to say, I shall hold myself at liberty to use any sufficient means for this purpose, and also any mode of applying the same.

So, also, to start and stop the machine, and to regulate its speed, I reserve the right of using the same means described in said patent, or any others that are the equivalents thereof.

Fig. 4 illustrates my mode of making my magnetizing-coils. I use flat wire or thin strips of metal in making them, which I wrap in a perfectly straight line, until I get as many folds or convolutions as I desire, as, for example, as shown at 1, and then fold over the strip of metal at right angles to the line of the coil just

completed, as shown at 2, and then again at right angles, as shown at 3, so as to make the direction of the wrapping in the second coil the same as in the first, and, as in that case, in such manner that each succeeding thickness or fold of wrapping shall be precisely over the preceding ones, as shown at 4, and so on until the coils are completed.

I am aware that flat wire has been used in making coils for magnets, and I do not, therefore, claim the use of the same for such purpose. My invention consists of the peculiar mode of making magnetizing-coils, which I have just described, and nothing beyond this do I pretend to consider my own.

The advantage resulting from my mode of construction, in addition to what I have already pointed out, is very great. There is far less resistance to the current of electricity than in spirally-wrapped coils, and, in consequence of the layers being brought as near as possible to the cores, a great diminution of the danger of consuming the zinc used, which is now generally

soon wasted from this cause, as well as less liability of crystallizing the copper, which, of course, puts it out of service, by a continued use of the engine for any length of time.

I claim, as my invention—

1. The multipolar electro-magnet C C' C'', when constructed and applied as described, in connection with the double-vibrating frame E, for the purpose set forth.
2. The double-vibrating frame E, in combination with the rectangular partially-hollow armatures D D', for the purpose set forth.
3. The mode herein described of making magnetizing-coils, for the purpose set forth.
4. The engine herein described, as a whole, for the purposes set forth.

A. E. DUPAS.
